[57] CLAIM

The ornamental design for a combined funnel and pouring spout, as shown and described.

DESCRIPTION

FIG. 1 is a front elevation of a combined funnel and pouring spout showing my new design, the rear, left, and right elevations are identical thereto;

FIG. 2 is an elevation axially rotated 45° in either direction from the view of FIG. 1;

FIG. 3 is a top plan view;

FIG. 4 is a bottom plan view; and

FIG. 5 is a section taken along the line 5—5 in FIG. 3.
